ABSTRACT: A control system for a conveyor movable in an endless path effects movement of the conveyor in the direction which will result in the shorter travel of a selected article on the conveyor when being brought to a fixed station. A readily calibrated dial for selecting a given article to be transported by the conveyor, and a circuit including a starting switch and a direction-selecting switch operable after such article has been selected as a result of adjustment of the dial, are disclosed.

DIAL CONTROL SYSTEM

BACKGROUND OF THE INVENTION

Many forms of conveyors movable in an endless path and carrying articles which are to be retrieved or loaded, at a fixed station convenient to the operator, are used, and in certain instances, as exemplified by the elevator control system disclosed in Lewis U.S. Pat. No. 1,856,876, the conveyor is caused to travel by the more direct path to the fixed station. The present invention employs this feature of reduced conveyor travel by means of an improved control system, and is particularly well suited for, but by no means limited to, use with conveyors found in establishments where laundry or clothing is being processed or stored.

In such establishments any delay, due to the additional time required for a long conveyor to bring a distant article by the longer rather than the shorter route to the unloading station, may result in annoyance or inconvenience to a customer as well as unnecessarily wasting the attendant's time while waiting for the article to arrive at that station. Thus, if the attendant's presence is required to keep the conveyor motor operating or to stop the same, a loss of his time, which otherwise could be employed in other duties, is involved. Moreover, in the use of automatic controls for such a conveyor system difficulty frequently is found in calibrating the conveyor and its control setting and keeping them in calibrated condition, especially when complex control circuits are involved. It is these and other difficulties experienced in the use of such conveyors which it is a purpose of this invention to overcome.

SUMMARY OF THE INVENTION

The invention comprises a control system for a conveyor having a plurality of article carriers movable in an endless path successively past a station and with means for selecting a given carrier and causing it to be moved to the station by the shorter route, and then stopped automatically thereat. The system includes a manually operable dial assembly which is selectively rotatable in either of two directions, and with the assembly having a first contact which, upon engaging a second contact, whose position is dependent upon conveyor movement, will interrupt the circuit leading to the motor which drives the conveyor. The circuit including these contacts also has a starting switch which remains inoperative until the first and second contacts are separated, and also includes a direction-selecting switch governing the direction of travel of the conveyor and whose position for so governing the travel direction is established by prior movement of the dial assembly.

Among the objects of the invention are the provision of a control system for a conveyor requiring the minimum amount of an attendant's time for effecting operation and stopping of the conveyor; the provision of an improved dial control system for a conveyor serving to move the conveyor in the direction which will bring a selected article carried by that conveyor to a fixed station by the shorter route, and to stop automatically at that station; the provision of a conveyor control system which may be easily calibrated or recalibrated in order to provide for the stopping of any predetermined portion of the conveyor at a preselected station along the path of the conveyor; the provision of a compact dial control assembly which may be mounted at a selected station, most convenient for an attendant, along a conveyor framework by being detachably secured to the framework; the provision of a conveyor control system with a circuit having an electrical transformer whose secondary is shunted when the conveyor is at rest thereby to avoid inadvertent restarting of the conveyor; and the provision of a conveyor control system having an operator-actuated toggle switch serving to move the conveyor in a selected direction while a normally operable automatic control system for the conveyor remains inoperative.

These and other objects and advantages of the invention will become more apparent as the description proceeds and when considered in conjunction with the accompanying drawings in which:

FIG. 1 is a perspective view, with parts broken away, of one form of conveyors, here shown as a garment storage and retrieving conveyor, with which the control system may be employed.

5 FIG. 2 is a front face view, to a larger scale, of the selector dial mounted on its housing.

FIG. 3 is a perspective view showing one arrangement for mounting the dial housing upon a conveyor framework.

FIG. 4 is a partial sectional view taken on line 4-4 of FIG.

10 2.

FIG. 5 is a partial sectional view taken on line 5-5 of FIG.

2.

FIG. 6 is a perspective view similar to FIG. 3, but taken rearwardly of the dial housing.

15 FIG. 7 is a detail view indicating the mounting of a garment hanger for the conveyor and in position to actuate the control mechanism.

FIG. 8 is a side elevation view partly in section and illustrating one modification of the drive for the dial shaft.

20 FIG. 9 is a sectional view to a smaller scale, taken on line 9-9 of FIG. 8.

FIG. 10 is an exploded perspective view of the interior face of the dial housing indicating relative positions of switches, shafts, and metal selector plate.

25 FIG. 11 is a schematic wiring diagram for the electrical components of the apparatus; and

FIG. 12 is a schematic diagram of certain mechanical and electrical components of the apparatus.

30 Referring first to FIG. 1, one appropriate type of conveyor with which the invention may be employed is a garment retrieving apparatus as shown by Golden U.S. Pat. No. 3,265,011, but, as will be understood, the present invention in its broader aspects is suitable for use with many forms of conveyors which move in an endless path. For purposes of illustration and not of limitation, therefore, the conveyor may include a framework with a return end generally indicated at 1 and a drive end generally indicated at 2 and with elongated parallel sidetracks 3 extending between the respective ends. The sidetracks as well as the return and drive ends of the structure

35 preferably comprise a tubular section 4 having a longitudinal slot 5 (FIG. 7) in one side thereof and extending the entire distance of conveyor travel. Transverse supports 6 and 7 attached to the tubular sections are in turn supported at a desired height by upright standards 8 provided with bases 9.

An array of pivotally interconnected links 10, on which article carriers may be supported, is in turn supported by a plurality of spaced hooks 11 attached at their lower ends to the links and terminating at their upper ends in generally horizontal portions 12 projecting through the slot 5 of the tubular track, as best shown in FIGS. 7 and 8. Intermediate its ends the hook 11 is provided with a laterally projecting portion 13, the purpose of which will later appear, and the extreme end of hook portion 12 is threaded and pivotally receives a matting

50 threaded bore formed in the central portion of a roller plate 14. At each end this plate 14 has threaded bores receiving bearing screws 15, 15A and upon these screws a pair of rollers 16, 16A are journaled for rotation within the tubular track and in contact with the lower interior surface of the track, as more fully disclosed in said U.S. Pat. No. 3,265,011.

With further reference to FIG. 1, a control assembly generally indicated at 17 is suitably mounted upon the conveyor structure at a convenient location for the attendant of the equipment, this location herein being called the "station," and which normally, but not necessarily, is adjacent the return end 1 of the conveyor. The control assembly includes a housing having apertured front and rear wall plates 18 and 19 respectively as well as side, top and bottom sections serving jointly to enclose certain mechanical and electrical components later to be described. Adjacent the drive end of the conveyor a gear motor 21 is provided for driving the array of

65 links 10 through a chain 21A connected to a drive wheel 22 engaging the array of links, such drive being in either a clockwise or counterclockwise direction as established by the prior setting of the dial control, now to be described.

Considering now FIGS. 2 to 5, a tubular support 25 is affixed normally to the rear wall 19 of the housing and within this support a shaft 26 is journaled for rotation in dependence upon the conveyor movement. A six tooth pinion gear 27 located within the housing is mounted at one end of shaft 26 and is driven thereby, while to the other end of the shaft 26 a symmetrical noncircular cam 28, for example of hexagonal shape, is rigidly attached. Six equally spaced radial fingers 29 project from the cam into the path of the portions 13 of the suspension hooks, as seen in FIG. 5, with the result that as the conveyor moves in either direction the shaft 26 and its pinion 27 is rotated 60° in the appropriate direction each time a finger 29 is pushed by the engaging hook. To prevent play of the related elements, a detent including a roller 30 carried by a lever 31 suitably mounted on a shield member 32 and with the roller biased into contact with the faces of the cam 28 by means of a compression spring 33, is provided. The shield 32 serves to protect the fingers 29 against damage which might result from the attendant handling garments at the station, and the action of the detent assures that the position to which the pinion 27 is rotated will remain synchronized with the location of the corresponding links of the conveyor.

As best seen in FIG. 5, the tubular support 25 has attached thereto a downwardly facing concave clamp 35 adapted to encompass an upper portion of the tubular track section 4. A companion clamp 36 which may be adjustably secured to the upper clamp 35, as by means of a bolt 37 provides for rigidly mounting the described control assembly and its attached parts to the conveyor structure at any desired location where the operator station is most convenient. As will be understood, the clamps 35 and 36 do not diminish the slot 5 nor interfere with the movement of the hook portions 12.

As a significant feature, pinion 27 is meshed with an electrically conductive, and much larger, spur gear 40 which is journaled for rotation on a fixed electrically conductive rod 41 attached at one end to a boss 42 on the inner face of the housing rear wall 19. This rod is connected to ground, as will later become evident. The distal end of rod 41 provides a mounting for a tubular shaft 43 which is formed of insulating material and which is journaled for rotation on the rod 41 independent of the rotation of gear 40 on the same rod. Preferably, the pinion gear 27 has six teeth, one tooth for each finger 29, and gear 40 is provided with one tooth for each link 10. Accordingly, a 50 link conveyor has a 6 tooth pinion and a 50 tooth gear; a 100 link conveyor has a 6 tooth pinion and a 100 tooth gear. Rigidly attached to shaft 43, as by means of set-screws 44, is a shaft 45 projecting through the front wall 18 of the housing and having an enlarged head 46 at its outer end.

As shown in FIG. 4, a metal plate 50 is rigidly affixed to the insulating shaft 43 in a plane normal to the shaft axis and is rotationally adjusted upon manual turning of the attached shaft 45. On its rear surface the plate 50 carries a rigid contact 51 herein called the first switch contact. Radially projecting from the confronting face of spur gear 40 and positioned in the orbital path of contact 51 is a flexible contact 52, herein called the second switch contact and whose position at any given time is indexed with respect to the corresponding links of the conveyor due to the engagement of the gear 40 with the indexed position of the pinion 27. As will be understood the contacts 51 and 52 establish an electrical circuit when in contact with each other and contact 52 is sufficiently resilient to permit relative movement thereof across the rigid contact 51 in either direction.

As indicated in FIGS. 4 and 10 a switch for determining the direction of conveyor movement is provided and conveniently may comprise a cylindrical lever 53 formed of insulating material and pivotally attached at one end by means of a pin 54 to a fixed bracket 55 extending inwardly from the front plate 18 of the control assembly housing. A carbon or graphite brush 56 having a flexible conductor 57 attached thereto is mounted within the lever 53 and is pressed at all times against the surface of plate 50 by means of a compression spring 58 housed within the cylindrical lever. As a result, rotational movement of plate 50 in one or the other direction will cause

the direction selection switch to pivot and to occupy either a first or a second circuit-energizing position, the purpose of which will later become apparent. As part of the direction selecting switch assembly a single-pole, double-throw toggle switch, FIG. 11, is mounted upon the stationary bracket 55 adjacent the lever 53 with its toggle leaf 60 arranged to be engaged and moved by that lever when the lever is moved in one direction and to be free from such engagement when that lever is moved in the other direction. A leaf-type, toggle spring 61 is arched between the end of the leaf 60 and the end of a movable contact 62 associated with the operator actuated dial selector now to be described.

Passing now to FIGS. 2 and 5, a dial-type selector disc 70 having uniformly spaced markings in the form of numerals or letters on its face is adjustably mounted on shaft 45 with a clutch arrangement. Rigidly attached to the disc is a knob 71 having a recess in its outer face and into which the head 46 is adapted to fit with a tight frictional engagement. One feature 15 of the present invention resides in the ease of calibration of the equipment and this is accomplished by having the selector dial or disc 70 spaced from the front plate 18 by a distance greater than the depth of the recess in head 46. A compression spring 72 interposed between the plate 18 and disc 70 serves 20 normally to hold the parts in engagement so that turning of knob 71 turns shaft 45 and its attached plate 50. However, by pushing the knob 71 and turning the disc 70 while the head 46 is out of the recess an adjustment in the relative angular position 25 of the disc 70 and the plate 50 may be effected.

As will be understood, the several markings on disc 70 correspond to the several links on the conveyor on which the articles are positioned and in order to retrieve a selected article at the station it is necessary to select the same by indexing the 30 disc with respect to a standard. Such a standard may comprise a fixed reference 73 on the face of plate 18 and for convenience in promptly noting the relative proximity of the next article to be retrieved, a cooperating mark 74 diametrically across the disc from mark 73 is provided. Thus, as illustrated, 35 in order to cause the more rapid retrieval of an article from link numbered nine the operator would rotate disc 70 counterclockwise and thus effect an equivalent movement of the conveyor through the circuits later to be described, while if an article from link numbered fourteen is to be retrieved he would 40 rotate disc 70 clockwise.

Referring now to FIGS. 11 and 12, a suitable transformer 80 includes a high-voltage primary 81 connected to lines 82, 83 and a low-voltage secondary 84 having leads 85, 86 extending therefrom and serving the control system. Leads 87, 88 from 45 the primary extend to a conventional motor reversing contactor 89 equipped with coil 90 associated with clockwise rotation of drive motor 21 and with coil 91 associated with counterclockwise rotation of that motor. The motor itself may conveniently be of the conventional capacitor start, single-phase, 50 alternating current type having a centrifugal starting switch including a bridging bar 92 cooperating with contacts 93, 94. The motor also comprises a running winding 95 for driving the conveyor and a starting winding 96 and with the capacitor 97 being in the circuit of winding 96.

The control system includes a contactor-controlling circuit having a pushbutton start switch 100, a push button stop switch 101, and a manually operable, normally open toggle-type switch 102 all mounted on the front plate 18 of the housing, and readily accessible to the operator at the station. Associated with the start switch 100 is an automatic coil 103 which when energized to establish a holding circuit causes ganged armatures 104, 105 to engage contacts 106, 107 respectively. The stop switch 101 normally engages contacts 108, 109 by its bridging bar 110, the contact 108 being connected to ground by a lead 111. The toggle switch 102 includes a manually operable arm 112 which optionally may be engaged with either contact 113, or 114, or with neither contact, and is intended for use when the transformer secondary 55 has been shunted in the manner later to be described.

OPERATION OF THE DIAL CONTROL SYSTEM

Assuming that the last article retrieved was from link number four of the conveyor and with the conveyor at rest, it will be noted that the spur gear 40 now occupies a position corresponding to the physical presence of that conveyor link number four at the station and that the plate 50 occupies a position with its contact 51 in engagement with the contact 52 of that spur gear. The holding circuit for coil 103 now being interrupted, the operator wishing to retrieve the article on link number 9 by the shorter path of conveyor travel now turns the disc 70 counterclockwise until the numeral 9 coincides with the reference 73. In so doing the plate 50 is suitably rotated to bring its first contact 51 five link spaces away from the second contact 52 of the spur gear 40 which is at rest. Simultaneously the turning of plate 50 causes the direction selection switch whose carbon brush 56 in electrical, as well as mechanical, contact therewith to move to a circuit engaging position corresponding to counterclockwise movement of motor 21. In so doing, the contact 62 (FIG. 11) is engaged with contact 120 which through leads 121 and 122 is connected to one terminal of the counterclockwise coil 91. The other terminal of this coil is connected by leads 123 and 124 to lead 85 at one terminal of the transformer secondary.

Upon pushing of start switch 100, coil 103 is energized through the contactor-controlling circuit from the transformer winding, leads 86, 125 and 126; switch contact 127, switch bar 128, switch contact 129, lead 130, coil 103, lead 131, contact 109 of the closed stop switch bar 110 and contact 108 of stop switch 101, and lead 85 to the transformer winding 84. Energizing of coil 103 causes armature 104 to engage contact 106 and armature 105 to engage contact 107. Thus, when armature 97 engages contact 106 a holding circuit is established and the operator is freed for other duties while the conveyor operates since he does not need to hold the start switch closed. The holding circuit, of course, is made from the transformer winding 84 through leads 86, 125, armature 104, contact 106, lead 132, coil 103, lead 131, and through the closed stop switch back to the transformer winding 84.

When, therefore, the described holding circuit is established, a motor-actuating circuit also is made ready from transformer winding 84 through lead 86, armature 105, contact 107, leaf 133, lead contact 62 (which had been moved in the selected direction as a result of movement of the disc 70), contact 120, leads 121 and 122, coil 91, and thence, to the transformer by leads 123, 124 and 85. As coil 91 is energized it causes the ganged armatures 135, 136 and 137 associated therewith to bridge the respective pairs of contacts 138, 139; 140, 141 and 142, 143. Simultaneously a circuit is established from the transformer primary through leads 87, 145, contacts 138, 139, closed by armature 135, lead 146, running winding 95, leads 147, 148 and 88 to the transformer primary 81. At the same time the starting winding of motor 21 is temporarily energized by the circuit through lead 150 connected to winding 95, contacts 93, 94, closed by the centrifugal starting switch bar 92, leads 151, 153, contacts 141, 140, closed by armature 136, lead 154, capacitor 97, winding 96, lead 155, contacts 143, 142, closed by armature 137 and leads 148 and 88 to the transformer primary 81. As will be understood, as soon as the motor 21 comes to approximately its running speed the bar 92 disengages from the contacts 93, 94 and the motor continues to run at its rated speed driving the conveyor in a counterclockwise direction until the following events occur.

As each of the conveyor links pass by the station, the projection 13 on the corresponding hook engages a finger 29 and turns the pinion 27 through 60°. With an appropriate gear ratio between pinion 27 and the spur gear 40 the second contact 52 is moved incrementally nearer the first contact 51 each time a link passes the station. Therefore, in the above example after five such movements of the spur gear, the chosen link number nine will arrive at the station simultaneously with the

contact 52 engaging contact 51. At this time the secondary 84 of the transformer 80 is shunted as follows. Since the rod 41 is grounded as by a wire 160 connected to any suitable ground and the terminal connection of contact 108 also is grounded 5 through lead 111, the grounded circuit is established from rod 41, gear 40, second contact 52, first contact 51, disc 50, brush 56, leads 57, 161, 132, contact 106, armature 104, leads 125, 86, secondary winding 84, lead 85, lead 111 to ground, as soon as the conveyor movement brings contact 52 into engagement with contact 51 and corresponding to the retrieval of the selected article at the station. When this occurs, the potential in the described holding circuit for coil 103 drops and that coil becomes deenergized thus shifting the armatures 104, 105 and opening the control circuit whereupon the described circuit to motor 21 also is opened by the simultaneous deenergization of the coil 91.

Significantly, this action which represents an important feature of the invention assures that mere reclosing of the switch 100 while the first contact 51 and the second 52 are still in engagement, will not restart conveyor movement. Rather, the operator must first select the next article to be retrieved and physically move the disc 70 before the conveyor can be automatically moved.

Assuming that the operator therefore selects the article at another link (involving for most rapid retrieval a clockwise movement of the conveyor and its motor 21), and moves the selector disc 70 accordingly to separate the first contact 51 and the second contact 52, it will be apparent that the secondary 30 of the transformer will no longer be grounded. Closing of switch 100 of course will again energize coil 103 as before described, but since the plate 50 has now been rotated in a different direction, the direction-selecting switch lever 53 will have thus been rocked to its second circuit-energizing position and with the leaf 62 now in engagement with contact 162 35 which is connected to a lead 163 extending to a terminal on the clockwise coil 90 via lead 170. A circuit thus is made through the leads 124 and 85 back to the transformer secondary and coil 90 is energized. Its energization causes the ganged armatures 164, 165, 166 to close respectively upon the contacts 144, 167; 149, 168; and 152, 169. During energization of the clockwise coil 90, a circuit is made from the transformer through lead 86, armature 105, contact 107, lead 133, leaf 62, contact 162, lead 163, lead 170, coil 90, and leads 124 and 85 to the transformer.

Closing these armatures establishes a running circuit for motor 21 as follows: from lead 87 of the transformer primary to contact 144, armature 164, contact 167, leads 171 and 146, running winding 95, and leads 147, 148 and 88 to the transformer. The starting winding 96 simultaneously is energized from lead 150, contact 93, bridging bar 92, contact 94, lead 151, contact 152, closed armature 166, contact 169, leads 173 and 155, starting winding 96, capacitor 97, leads 154 and 172, contacts 168, 149, closed by armature 165, and lead 88 to the transformer primary. As will now be evident the starting winding is energized in a direction opposite to that described above for counterclockwise rotation of motor 21 and thus the motor is started in a reverse or clockwise direction which corresponds to the setting established earlier by the operator when he moved the selector disc 70.

As before, when the motor 21 comes up to speed the centrifugal starting switch causes bridging bar 92 to disengage contacts 93, 94 and the motor will run in its clockwise direction, since its winding 95 will remain energized until the conveyor is again stopped by engagement of the moving second contact 52 against the stationary first contact 51.

Under some circumstances the conveyor operator may wish to employ a control enabling him to move the conveyor in a chosen direction even while coil 103 is deenergized. The arm 70 112 of the toggle switch 102 normally is out of engagement with contacts 113 and 114, but when moved by the operator into engagement with contact 113, for example, a circuit causing energization of the counterclockwise coil 91 will be made as follows even though control coil 103 is deenergized. Thus, a

circuit will be established from the transformer secondary through leads 86 and 125, armature 104, contact 180, lead 181, arm 112, contact 113, lead 122, coil 91, leads 123, 124 and 85 back to the transformer. Likewise, when the operator moves arm 112 of the toggle switch 102 into engagement with contact 114 (the control coil 103 being deenergized) a circuit is established from the secondary through leads 86 and 125, armature 104 contact 180, lead 181, arm 112, contact 114, lead 170, the clockwise coil 90, leads 124 and 85 back to the transformer. In each situation, the energization of one of the coils 91 or 90 will effect the drive of motor 21 in its chosen direction, ut not control circuit through coil 103 and the leaf 62 of the direction selecting switch is being exerted. When the operator, therefore, wishes to bring the motor to a stop he merely moves the switch arm 112 to its normal position out of engagement with either of contacts 113 or 114.

In addition, and for safety purposes, the stop switch 101 is provided for cancelling the automatic operation of the conveyor, and when opened by depressing the bridging bar 110 will open the above-described holding circuit of the automatic control coil 103.

Having thus described the general operating circuits of a preferred form of dial control system, it will be apparent that certain mechanical features of the apparatus are important as well. For example, the control assembly may be compactly arranged in the housing which can be readily mounted on the conveyor framework at the desired location which is to serve as the operator station. As seen in FIG. 10, the start switch 100, stop switch 101, toggle switch 102, bracket 55 and coil 103 are mounted on the inner surface of the plate 18 of the housing which, of course, is sufficiently large to accommodate the gear drive and the rotatable plate 50. In this gear drive, the ratio between the pinion 27 and the spur gear 40 is such as to provide for one complete revolution of gear 40 for one complete circuit of a given link of the conveyor around the conveyor track. Preferably, the tubular support 25 is mounted in a slot (not shown) in the removable backwall 19 of the housing, so that when the control assembly is to be employed on a conveyor having a lesser, or a greater number of links, that support may be positioned at a lesser or a greater distance from the axis of rod 41. In this way a different gear 40 may be employed so as to retain the proper ratio of revolutions of the plate 50 and the length of conveyor. Also, the selector disc 70 is readily removable from the shaft 43 so that a different selector disc suitable for use with that different conveyor length may be installed when the gear 40 is changed.

In the event that it is desired to have the control knob 71 at a lower elevation, a longer housing may be used as seen in FIGS. 8 and 9. In this embodiment spaced auxiliary stub shafts 185 and 186 are mounted on the rear wall 19 of the housing and the conveyor-driven shaft 26 enters that rear wall at a higher elevation well above the axis of the stationary rod 41. The spur gear 40 journaled on rod 41 is in mesh with pinion 27 which in turn forms part of a pulley 187 journaled on stub shaft 185. A timing belt 188 drives this pulley and is driven by a pulley 189 affixed to the conveyor-driven shaft 26. The timing belt also passes around a takeup pulley 190 journaled for rotation on the stub shaft 186. The stub shafts 186 and 185 are each adjustable in slots (not shown) in the wall 19 to permit the required changing of gear 40, as hereinbefore described, and to adjust tension on belt 188. This belt 188 is of the conventional type having toothlike elements on its driving surface engaging similar elements on the several pulleys and maintaining register of movement of the rotating parts. As will be obvious, with this timing belt drive the ratio between the conveyor length and the single rotation of gear 40 may, as an alternate, be accomplished by proper choice of the size of pulleys 189 and 187 as well as the choice of ratio between pinion 27 and spur gear 40.

With the foregoing description in mind the several objects of the invention will now be apparent. Upon installation of the equipment the operator knows the number of identified links 11 of the conveyor and has available for use therewith a selec-

tor disc 70 with a commensurate number of markings thereon and a plate 50 connected to a gearing which will cause that plate to make one revolution when a given link of the conveyor travels one complete circuit around the conveyor track. Accordingly, the operator then declutches the selector disc by pressing upon knob 70 and turns the disc 70 until its marking corresponds with the conveyor link then resting at the operator station. The knob is then released and spring 72 causes the disc 70 to engage with shaft 45. The operator then operates the conveyor several times in both its clockwise and counter-clockwise directions to make sure that it will stop each time with a selected link at the operator station. If a misalignment, or improper engagement for example of a finger 29, is detected, such is then easily corrected by depressing knob 71 and resetting disc 70.

Moreover, the combined electrical circuitry and mechanical components are such as to cause the conveyor to move in the most expeditious and shorter route when an article is being retrieved. Furthermore, the shunting of the transformer secondary after the conveyor comes to rest prevents further motion of the conveyor until either the toggle switch is operated, or else a new link is selected followed by a closing of the start switch.

As will be understood, the positioning of shaft 26 by reason of fingers 29 being moved by the projections 13 on the travelling hooks 11 is not the sole way of driving the shaft and such a drive may be accomplished by other means without departing from the invention. For example, shaft 26 could be moved by a flexible shaft connected to the rotatable drive wheel 22; or a timing belt driven by that wheel could connect that wheel and shaft 26; or a rigid line shaft system could connect the drive wheel 22 and shaft 26.

Having thus described and illustrated the preferred embodiments of the invention, it will be understood that the invention may also be embodied in other forms within the scope of the appended claims.

I claim:

1. For use with a conveyor having a plurality of article carriers movable in an endless path successively past a station and with means for selecting a particular one of said carriers and causing it to be subsequently moved to said station by the shorter route and stopped thereat; a control system comprising an electrical circuit including a motor for driving said conveyor in either of two directions, a manually operable dial selectively rotatable in either of two directions and arranged to remain at rest while said motor is energized, a first switch contact connected to said dial and adapted to rest in a position corresponding to the dial setting, a second switch contact movable in dependence upon the movement of said conveyor and in correspondence with the position occupied by one of the carriers of said conveyor, a movable direction-selecting switch actuated by movement of said dial and adapted to occupy either a first or a second circuit-energizing position in dependence upon the movement of said dial in the selected direction, and a starting switch operable to start said motor following the positioning of both of said first switch contact and said direction-selecting switch, said circuit being deenergized and said motor being stopped when said second switch contact is moved by said conveyor into engagement with said first switch contact.

2. A control system as defined in claim 1 including a normally engaged clutch interposed between said dial and said first switch contact, said clutch serving to provide for calibration of the conveyor carriers with the dial settings, said dial being adapted to be moved to a selected position without moving said first contact when said clutch is disengaged and to move with said dial when said clutch is engaged.

3. A control system as defined in claim 2 including a knob on said dial adapted to be pressed axially of said dial against the bias of a spring thereby to disengage said clutch.

4. In a control system for a conveyor having a plurality of article carriers movable in an endless path, an electrical circuit including a transformer having a primary and a secondary, a

motor for driving said conveyor in either of two directions and connected to said primary through a reversing contactor, means for actuating said contactor and comprising a contactor-controlling circuit connected to said secondary and to said contactor and including a first switch contact carried by a dial selectively movable in either of two directions, a second switch contact movable in dependence upon movement of said conveyor and in correspondence to the position occupied by one of the carriers of said conveyor, a movable direction-selecting switch actuated by movement of the dial and adapted to occupy either a first or a second circuit-energizing position in dependence upon the movement of the dial in a selected direction, and a starting switch operable to start said motor following the positioning of both of said first switch contact and said direction-selecting switch, said contactor-controlling circuit being deenergized and said motor being stopped by shunting of said secondary when said second switch contact is moved by said conveyor into engagement with said first switch contact thereby to prevent further automatic movement of said conveyor by operation of said starting switch prior to separation of said first and said second switch contacts.

5. A control system as defined in claim 4 including a normally open, manually operable switch in said contactor-controlling circuit and adapted to energize said contactor by removing said shunting of the transformer secondary independently of operation of said starting switch, said manually operable switch being selectively movable to positions causing said contactor to establish circuits from said primary to said motor for driving said motor in either a clockwise or counter-clockwise direction.

6. In combination, a conveyor supported for orbital path movement around an endless rail mounted on a framework, said conveyor having an array of depending links for carrying articles in spaced relation to each other, a reversible electrical motor for driving said conveyor in either of two directions, a control system for causing said motor to drive said conveyor in the shorter direction to bring a selected link to a stationary station and to stop thereat, a housing for said system detachably mounted on said rail at said station and having a front wall and a rear wall, a conveyor-driven shaft projecting from said rear wall and carrying means engageable with said

conveyor, a second switch contact rotatably mounted in said housing and driven by said conveyor-driven shaft and occupying a position corresponding to the location of a chosen link in the conveyor orbital path, a dial-selector shaft projecting from the front wall of said housing and adapted to remain at rest while said motor is energized, a first switch contact disposed in said housing and occupying a position corresponding to the angular setting of said dial-selector shaft, means for selectively rotating said dial-selector shaft for determining the link to be moved to said station, and electrical circuit means in said control system for causing said motor to operate and to drive said conveyor to bring said second contact into engagement with said first contact and to deenergize said motor when said contacts engage each other.

15. 7. Apparatus as defined in claim 6 including a movable direction-selecting switch in said circuit means adapted to occupy either a first or a second selected circuit-energizing position determining the direction of rotation of said motor, said direction-selecting switch being moved to the selected position by rotation of said dial-selector shaft.

8. Apparatus as defined in claim 6 wherein said means for rotating said dial-selector shaft includes an exposed dial spaced from said housing and having indicia thereon corresponding to the number of links on said conveyor, said dial including an operating knob joining said dial to said dial-selector shaft.

9. Apparatus as defined in claim 6 wherein said first switch contact is carried by an electrically conductive plate mounted in insulated relation upon said dial-selector shaft and in fixed relation thereto.

10. Apparatus as defined in claim 6 wherein each of said first and second switch contacts are flexibly mounted whereby each contact may be moved in either direction across the other.

35. 11. Apparatus as defined in claim 6 wherein said means for engaging said conveyor with said conveyor-driven shaft comprises a plurality of fingers attached to the shaft and equally spaced angularly from each other, said fingers projecting into the path of movement of the suspension hooks of said links 40 thereby to turn the shaft a commensurate distance as each hook engages each finger.
